UNITED STATES PATENT OFFICE.

HOMER W. CASE, OF POUGHKEEPSIE, NEW YORK.

SIFTER.

1,087,727.

Specification of Letters Patent.

Patented Feb. 17, 1914.

Application filed August 28, 1912. Serial No. 717,536.

To all whom it may concern:

Be it known that I, HOMER W. CASE, a citizen of the United States, residing at Poughkeepsie, in the county of Dutchess and 5 State of New York, have invented new and useful Improvements in Sifters, of which the following is a specification.

This invention relates to sifters and more particularly to that type which are specifically adapted for sifting dry insecticide or 10 like material over the plants.

One of the principal objects of the invention is to improve upon former Patent No. 934,283, granted September 14, 1909, which 15 cannot be used successfully and accurately upon small plants and the amount of discharge cannot be regulated in any way except by governing the turning of the receptacle by the operator.

20 The object of this invention therefore is to provide a sifter which may be conveniently used upon small or large plants and having such construction that the discharge may be conveniently governed in accordance 25 with the quantity desired to be expelled and with the material being used.

Further objects of the invention will appear as the following specific description is 30 read in connection with the accompanying drawing which forms a part of this invention and in which:

Figure 1 is a side elevation. Fig. 2 is a vertical sectional view therethrough. Fig. 3 is a bottom plan view. Fig. 4 is a detail showing the bottom closing plug in position to 35 cut off discharge through the bottom of the sifter.

Referring more particularly to the drawing 1 represents an elongated substantially 40 cylindrical receptacle having a cap limit rib 2 formed adjacent its upper edge and being provided with a closing cap 3, the receptacle is supported and operated by a bail shaped handle 4 and has its lower end provided with an outstanding circumferential flange and closed by a foraminous bottom 5 which is journaled or otherwise secured to the receptacle and forms in effect a continuation of the foraminous portion 6 at the 45 lower end of the receptacle. When the sifter is used upon very small plants it is desirable that the perforations in the portion 50 6 be entirely closed and the perforations

in the bottom 5 used. To cut off the discharge through the perforations in the portion 6 or to regulate the discharge through 55 said perforations a sleeve or collar 7 surrounds the receptacle 1 and is slidably mounted thereon being held in adjusted position by means of friction. The outstanding flange at the lower end of the receptacle forms a stop to prevent the regulator frame from being casually detached. The preferred type of regulator is a split paste 60 board ring held in engagement with the receptacle by means of elastic bands 8 as shown. As the vines continue to grow the side perforations can be readily exposed to a degree necessary to produce proper sprinkling of the plants when these vines or bushes 65 get very large and form a continuous row, if the bottom is left open and the sifter continuously operated there would be too much material distributed in the center of the row thereby causing waste, to avoid this a plug 70 9 of paste board or other suitable material is furnished with each sifter and may be placed upon the bottom 5 to entirely close the perforations therein. The side perforations may then be regulated by shifting the 75 collar 7. As will be readily understood this collar may be of any suitable material but paste board is preferably used on account of the fact that it hangs close to the receptacle and is not affected by being dented 80 which would be the case if metal were used.

The device is operated for either small or large plants in a similar manner by holding the receptacle over the plants and resiliently twisting or turning same in opposite directions.

What is claimed is:—

1. The herein described sifter comprising a vessel having a foraminous bottom and also having the lower portion of its walls 95 perforated, and further provided with an outstanding stop flange at its bottom, a split sleeve extending around the wall of the vessel, and means on said sleeve to cause the sleeve to frictionally engage with the vessel and hold the sleeve in adjusted position, the sleeve being adapted to be moved over or removed from the perforated lower portion 100 of the wall, for the purpose set forth.

2. The herein described sifter comprising 105 a cylindrical vessel having a foraminous

2
bottom and also having the lower portion of its wall foraminous and provided with a stop flange, a sleeve arranged around the walls of the vessel and open at one side and elastic bands passing around the sleeve, holding it in closed position and frictionally engaging the sleeve with the wall of the vessel to secure the sleeve in any desired

adjusted position, the stop flange preventing casual detachment of the sleeve.

In testimony whereof I affix my signature in presence of two witnesses.

HOMER W. CASE.
